Term of patent 14 years

Int. Cl. D12—16
U.S. Cl. D14—27

FIG. 1 is a perspective view of a luggage rack showing my new design;

FIGS. 2 and 3 are enlarged perspective views of portions thereof looking in the directions of the arrows 2 and 3, respectively;

FIG. 4 is a cross-sectional view, taken on the line 4—4 in FIG. 3.

The portion of a motor vehicle shown in broken lines in FIG. 1 is included for illustration purposes only.

I claim:

The ornamental design for a luggage rack, substantially as shown and described.
